GAS BLAST BREAKER WITH SEPARATELY ACTUATED BLAST VALVE AND TANK FILLING VALVE

Gustav E. Jansson, North Quincy, Mass., assignor to Allis-Chalmers Manufacturing Company, Milwaukee, Wis., a corporation of Delaware

Application July 11, 1947, Serial No. 760,258

15 Claims. (Cl. 200—81.4)

1

The present invention relates to electric circuit breakers of the gas blast type, and more particularly to means for preventing re-establishment of the arc subsequent to a current zero with a minimum of consumption of arc extinguishing fluid.

The operation of gas blast circuit breakers requires a high initial blast intensity for establishing a high dielectric level across the gap formed between the separated contacts. Upon having established the required dielectric level, the same may be maintained by means of a blast of smaller intensity.

There exists for any given set of conditions a most desirable blast intensity-time characteristic. In order to operate a circuit breaker with a minimum consumption of arc extinguishing fluid, the actual blast intensity-time characteristic must be as close as possible to the blast intensity-time characteristic which would be ideal under prevailing conditions.

Various arrangements may be used for obtaining any desired blast intensity-time characteristic. For instance, arc extinguishing gas under pressure, e. g. compressed air, may be supplied from a blast reservoir or breaker tank having a relatively limited capacity not substantially exceeding that required for one single interrupting process or may be, two interrupting processes. Upon initiation of the escape of arc extinguishing fluid from a one-shot-tank, the pressure therein decreases rapidly, resulting in a rapid decrease of the blast intensity. Thus the blast intensity decreases rapidly to the relatively small magnitude required after circuit interruption for maintaining for a short time the proper dielectric level across the gap formed between the separated breaker contacts until additional circuit insulation can be introduced into the circuit. Because of this rapid decrease of blast intensity, a gas blast circuit breaker having a one-shot or similar small tank permits to be operated with a minimum consumption of arc extinguishing fluid.

Yet one-shot tank type circuit breakers are unsatisfactory in certain respects. Since it takes time to refill a blast reservoir or breaker tank by means of a compressor, one-shot-tank type circuit breakers are inapplicable wherever it is required to effect more than one interrupting operation within a relatively short interval of time as, for instance, in the case of high-speed reclosing service.

For this reason it has become accepted practice, in cases involving a duty cycle comprising

2

more than one interrupting operation occurring within a short interval of time, to provide gas blast circuit breakers with a blast reservoir or breaker tank having relatively large dimensions and sufficient storage capacity to supply the amount of arc extinguishing fluid required for a plurality of interrupting operations. In circuit breakers having such oversized breaker tanks there is, subsequent to initiation of the escape of an arc extinguishing gas blast therefrom, a slow decrease of the tank pressure. This results in maintaining a gas blast of larger magnitude than required for preventing re-establishment of the arc after initial arc extinction. Consequently, such arrangements are uneconomical.

Another type of gas blast circuit breakers comprises a blast reservoir or breaker tank from which the arc extinguishing blast is derived, and, in addition thereto, another fluid reservoir or storage tank which is connected to the blast reservoir or breaker tank by a fluid conduit of relatively large cross-section. That fluid conduit is controlled by a differential valve which is normally biased to the open position thereof, but closes when, owing to opening of the blast valve of the circuit breaker, the difference in pressure between the two aforementioned reservoirs or tanks increases beyond a predetermined value. Since the drop of pressure occurring upon opening of the blast valve is very rapid, this results in rapid closing of the differential valve, thus making it possible to obtain a favorable blast intensity-time characteristic similar to that which can be obtained when using a one-shot or similar small-capacity tank. This type of circuit breaker comprises, in addition to the differential valve-controlled tank-interconnecting conduit which has a relatively large cross-section, a tank interconnecting conduit of relatively smaller cross-section, which is permanently open. Upon closing of the blast valve the pressure in the blast reservoir or breaker tank increases gradually owing to the leakage flow of gas under pressure through the permanently open tank interconnecting conduit of relatively small cross-section. When, owing to that leakage flow, the pressure in the breaker tank reaches a predetermined value, the large tank-interconnecting conduit is opened by the operation of the differential valve which is arranged therein, thus resulting in equalization of the pressure within the two tanks. It is apparent that it requires a relatively long time for the leakage flow between the two tanks to cause the differential valve to open and to make the circuit breaker thereby ready for a sec-

ond circuit interrupting operation. For this reason circuit breakers which are provided with a differential valve-interconnected two-tank pressure fluid system do not lend themselves very readily to applications involving rapidly recurring circuit interruptions as required, for instance, in the case of high-speed reclosing service. Nor do such circuit breakers lend themselves to a perfect coordination of the operation of the blast valve and the tank interconnecting valve.

It is, therefore, one object of the present invention to provide a circuit breaker of the fluid or gas blast type which permits rapid sequential interrupting operations with a minimum of consumption of arc extinguishing fluid or gas and which lends itself to high-speed reclosing service.

Another object of the present invention is to provide a circuit breaker of the type comprising a breaker tank, a storage tank, and a valve interconnecting said two tanks wherein said valve is positively actuated independently of the difference in fluid pressure between said tanks.

Another object of the present invention is to provide a circuit breaker comprising a pressure fluid system of the two-tank type wherein the valve for replenishing the breaker tank from the storage tank is opened instantly by positive action upon complete interruption of the circuit rather than being opened by spring or similar means after a predetermined time delay following reclosing of the blast valve.

Another object of the present invention is to provide a circuit breaker of the aforementioned type wherein the valve for replenishing the breaker tank from the storage tank is closed at the point of time of opening of the valve which controls the arc extinguishing blast rather than being closed only subsequent to the opening of said blast valve.

A still further object of the present invention is to provide a circuit breaker of the aforementioned type wherein a motor which must be present in the circuit breaker on account of reasons not related to the tank-interconnecting valve is used, in addition to its primary function, for operating said valve.

Objects and advantages other than those above described will be apparent from the following description when read in connection with the accompanying drawing, in which:

Fig. 1 is a view, partly in vertical cross-section and partly in side elevation, of a circuit breaker of the axial blast type, designed for outdoor service, and embodying the features of the present invention;

Fig. 2 is a diagrammatic representation of a circuit breaker of the cross-blast type, designed for indoor service, and embodying the features of the present invention; and

Fig. 3 shows a cross-section through certain details of a modification of the mechanism for operating the tank-interconnecting valve.

Referring more particularly to the drawing by characters of reference, Fig. 1 illustrates a high voltage circuit breaker comprising a movable contact 1 which cooperates with a tubular stationary contact 2 to make or break an electric circuit. Movable contact 1 is operated by a toggle linkage 3 which is actuated by a reciprocating rod 4. Flexible conductor 5 connects contact 1 to the terminal element 8. Movable contact 1 is arranged within a tubular insulator 6 forming an arcing chamber. The stationary contact 2 supports a tubular insulator 7 covered by a hood 7a which serve as an exhaust as well as a cool-

ing means for arc products. The upper part and the lower part of the circuit breaker column are provided each with a terminal element 8. The lower terminal element 8 is connected by means of conductor 8a to the terminal element 8d of a disconnect switch which has been generally indicated by the reference number 8. Disconnect switch 8 is adapted to be operated by a fluid motor 10 comprising a cylinder 10c, a piston 10d and venting means not shown in the drawing. The tubular insulators 8a form a housing for accommodating the contact members 8b, 8c of disconnect switch 8. Stationary tulip shape contact 8b, arranged on the top of the upper insulator 8a, is adapted to cooperate with the movable rod shape contact 8c. The latter may be actuated by fluid motor 10 through the intermediary of rock shaft 10b and crank mechanism 10a. If both the circuit breaker proper and the disconnect switch 8 are closed, the following circuit is established: Upper terminal element 8, contact members 2, 1, lower terminal element 8, conductor 8a, terminal element 8d, contact rod 8c, and tulip shape contact 8b. Contacts 1, 2 and contacts 8b, 8c, are supposed to be opened sequentially, the former for effecting initial circuit interruption and the latter for interposing additional circuit insulation into the circuit upon interruption thereof by separation of contacts 1, 2 and the action of an arc extinguishing blast.

A tubular insulator 11 supports the circuit breaker column consisting of the tubular insulator 8 and the aforementioned parts which are associated therewith.

35 A source of fluid under pressure, such as the compressor 12, may supply fluid under pressure through a pipeline 13, including check valve 14, to the storage reservoir or storage tank 15. Storage tank 15 is connected by means of tubular structure 16 to breaker tank 17. Breaker tank 17 has sufficient storage capacity for effecting one or two circuit interruptions. Pipe 18, which includes a check valve 19, is adapted to supply breaker tank 17 with fluid under pressure directly from compressor 12. It will be noted that the cross-section of pipes 13 and 18 is relatively small, while the cross-section of tubular structure 16 is relatively large. Blast tube 20 connects breaker tank 17 and tubular supporting insulator 11. The flow of fluid under pressure from tank 15 to tank 17 is controlled by valve 21. Valve 21 is biased to the closed position thereof by spring 22. It can be opened, against the action of said spring, by means of fluid motor 10, rocking shaft 10b, and a crank mechanism including push rod 23. Push rod 23 is connected to actuator 24 adapted to pivot about fulcrum 25.

60 In Fig. 1 rocking shaft 10b is shown in a position causing separation of contacts 8b, 8c and opening of valve 21 against the action of biasing spring 22. If rocking shaft 10b is rotated by motor 10 in a clockwise direction, this causes contact 8c to engage contact 8b and frees stem 26 of valve 21, thus permitting biasing spring 22 to reclose that valve.

65 Blast tube 20 is under the control of a blast valve which has generally been indicated by reference sign 27. Blast valve 27 is adapted to be operated by a fluid motor of the differential type which includes a cylinder 28a, a piston 28b, and a biasing spring 28c. Piston 28b serves as movable valve body and is adapted to engage valve seat 28d, and spring 28c tends to keep valve 27 in the closed position thereof. Oper-

tion of fluid motor 27 may be initiated by operation of solenoid trip valve 29. Normally fluid under pressure is being supplied to both sides of piston 28b, the left side of cylinder 28a being supplied with fluid under pressure from tank 17 through pipe 30. Upon energizing of solenoid trip valve 29, the left end of cylinder 28a is vented to atmosphere, thereby causing blast valve 27 to open.

Passage 31 is adapted to supply a fluid motor which has been generally designated by reference numeral 32 with fluid under pressure derived from the inside of insulator 6. Fluid motor 32 which includes a relatively movable cylinder 39 and piston 36 is adapted to operate operating rod 4 for separating contacts 1 and 2. Air under pressure flowing through passages 31 causes piston 36 of fluid motor 32 to move from right to left, resulting in moving operating rod 4 from right to left, and consequently in separation of contacts 1 and 2. Spring 31 biases motor 32 to contact closed position and effects closing of contacts 1 and 2 upon closing of blast valve 27. Cylinder 39 is adapted to be vented during the closing stroke of the breaker by means of air ducts 34 which are controlled by a check valve 35.

Normally blast valve 27 is closed by reason of the action of its biasing spring 28c. When trip valve 29 is energized, the left side of cylinder 28a is vented, while air under pressure acting upon the right end surface of piston 28b causes valve 27 to open. When piston or valve body 28b of blast valve 27 is lifted from its seat 28d, a blast of fluid under pressure rushes through blast tube 20 and tubular supporting insulator 11 into the arcing chamber formed by tubular insulator 6. The portion of the blast which branches off through conduit 31 causes the contacts 1, 2 to separate, as described above. An arc is initiated between the separating contacts 1, 2 and is acted upon by a blast of arc extinguishing gas under pressure which escapes through contact 2, insulator 7 and hood 7a. The blast storage capacity of tank 17 is sufficient for at least one complete interrupting operation, i. e., that tank is capable of supplying one initial high-intensity blast and one subsequent low intensity blast which lasts until the contacts 9b, 9c of the disconnect switch 9 have parted a safe distance. Consumption of fluid under pressure beyond the quantity needed for arc extinction and for maintaining temporarily the required dielectric level between the separated contacts 1, 2, is strictly precluded by reason of the fact that tube 16 remains closed as long as valve 21 is not opened by the operation of motor 10. Valve 21 is being opened while fluid motor 10 completes its stroke separating contacts 9b, 9c, thus rapidly increasing the pressure level in tank 17 to the amount required for a subsequent interrupting operation.

Conduit 18 helps increase the speed of restoring pressure in tank 17 by fluid under pressure directly derived from compressor 12, but may be omitted if this particular feature is not deemed necessary.

Fluid motor 10 is supplied with fluid under pressure through pipe 40 branching off blast tube 20 at a point situated downstream with respect to blast valve 27. Sequential contact separating operations of fluid motors 32 and 10 can be insured by proper selection of the cross-sections of fluid conduits 31 and 40 and proper adjustment of needle valve 40a.

Upon interruption of the circuit, contacts 1, 2 are being reclosed by the action of spring 31. This, however, does not result in reclosing of the circuit, since contacts 9b, 9c are separated before contacts 1, 2 are reclosed. Reclosing of the circuit is effected by causing contacts 9b, 9c to re-engage while contacts 1, 2 are in engaged position. Upon energization of closing solenoid valve 41, fluid under pressure is allowed to rush through pipe 42 to fluid motor 10, resulting in closing of contacts 9b, 9c and freeing of stem 26 of valve 21, thus permitting biasing spring 22 to close that valve.

In Fig. 2 the same reference numerals as in Fig. 1 have been supplied to like parts. Thus, 15 indicates a storage tank, 17 a breaker tank, 16 passage means interconnecting tanks 15 and 17, and 21 a valve for controlling the flow of fluid through passage means 18. Stem 26 of valve 21 is biased to the closed position thereof by means of biasing spring 22. Tank 15 can be supplied with fluid under pressure (from a source not shown) through pipe 13 and check valve 14. Tank 17 can directly be supplied with fluid under pressure through by-pass pipe 18 and check valve 19. Blast valve 27 controls the flow of fluid through blast tube 20. The electrical circuit of the breaker comprises upper terminal member 8, stationary finger contacts 2 adapted to engage movable contact 1, movable blade contact 1, and lower terminal member 8. Contact 1 is hinged at 43 and can be operated by means of fluid motor 32 comprising cylinder 39 and piston 36 operatively arranged therein. Pipe 31 is adapted to supply one of both ends of cylinder 39 with fluid under pressure. A linkage including piston rod 44 interconnects piston 36 and lever 45. Lever 45 is journalled in bearing 47. Operating rod 46 is hinged to contact 1 and lever 45, respectively. A projection 45a on lever 45 is adapted to engage stem 26 of valve 21 for moving said valve into the open position thereof. The circuit breaker comprises further an arc chute 50 including a plurality of arc splitters or partitions 51, which subdivide the chute into a plurality of blast passages 48. Partitions 51 converge toward the blast entrance and diverge toward the exhaust portion of chute 50. Blast valve 27 is adapted to be operated by fluid motor 28 which may be supplied with fluid under pressure from tank 17 through pipe 30 and solenoid trip valve 29. Opening of the latter causes fluid motor 28 to be supplied with fluid under pressure, resulting in opening of blast valve 27. This, in turn, causes a blast of fluid under pressure to rush through blast tube 20 and arc chute 50. Branch conduit 31 supplies fluid motor 32 with fluid under pressure. Fluid motor 32, upon being supplied with fluid under pressure, rotates lever 45 about fulcrum 47 in a clockwise direction. This causes separation of contacts 1 and 2 and the arc formed therebetween is extinguished by the blast of gas under pressure flowing through blast tube 20. The arc will be extinguished and the circuit interrupted before contact blade 1 leaves arc chute structure 50. During the initial separation of contacts 1, 2 extension 45a of lever 45 does not engage stem 26 of valve 21 and, therefore, valve 21 remains closed. It is necessary, upon extinction of the arc, i. e., interruption of the circuit, to interpose additional insulation into the circuit by increasing the amount of separation of contacts 1 and 2. To this end, fluid motor 32 is caused to move lever 45 and contact blade 1

until they reach the respective positions which have been indicated in Fig. 2 in dotted lines. Towards the end of its course, lever 45 engages stem 28 of valve 21 by means of extension 45a, thus causing rapid refilling of tank 17. Valve 21 remains open as long as the breaker contacts 1, 2 remain in their fully open position. Passage 16 may be provided with a check valve 52 for the purpose of preventing backflow of fluid under pressure from tank 17 to tank 15.

Opening of solenoid closing valve 38 causes fluid motor 32 to be supplied through pipe 59 with fluid under pressure from tank 17 and to close the breaker, simultaneously permitting biasing spring 22 to reclose valve 21, thus precluding any further flow of fluid from storage tank 15 to breaker tank 17.

Referring now to Fig. 3, this figure shows a storage tank 15, a breaker tank 17 and a tank interconnecting valve 21 arranged in a passage 18. Valve 21 comprises the stem 28 and the closing biasing spring 22. The flow of fluid through blast tube 28 and branch tube 40 is controlled by means of blast valve 27. Tube 40 branches out into branches 40a and 40b adapted to supply simultaneously both ends of a cylinder 53 with fluid under pressure. Piston 54 which is operatively arranged in cylinder 53 remains in its upper position as long as blast valve 27 remains closed, it being held in that position by the action of valve biasing spring 22. Passage 40a is provided with a check valve 55 and the head of cylinder 53 is provided with needle valve 56. If fluid under pressure is supplied simultaneously through branch passages 40a and 40b in front and back of piston 54, this will initially have no effect whatever on piston 54. Upon reclosing of blast valve 27 there will be a backflow of fluid under pressure from cylinder 53 through branch pipe 40b into blast tube 28. Owing to the presence of check valve 55 a similar backflow cannot occur from cylinder 53 through branch pipe 40a. Consequently, the pressure on one side of piston 54 will soon exceed the pressure on the other side thereof, resulting in a downward movement of piston 54, whereby valve 21 will be opened. The point of time at which piston 54 will open valve 21 can be properly adjusted by means of needle valve 56, the adjustment of which affects the rate of bleeding of the top of cylinder 53.

Since the backflow of fluid under pressure from cylinder 53 to blast tube 28 will be initiated upon reclosing of blast valve 27, it follows that reclosing of valve 27 and opening of valve 21 are effected sequentially. This sequence is important in order to preclude replenishing of tank 17 from tank 15 prior to reclosing of valve 27 which, if permitted to occur, would result in a waste of fluid under pressure.

A similar sequential operation of valves 27 and 21 can be achieved by the means shown in Fig. 1. To this end, an auxiliary switch 58 is included into the circuit of trip solenoid valve 29, which switch is under the control of motor 18 in such a way as to cause opening of the circuit of trip solenoid valve 29 sufficiently prior to the opening of valve 21 by rocking shaft 10b.

Although but some embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In a circuit breaker the combination of a pair of cooperating contacts, contact separating means, a source of fluid under pressure, a first reservoir adapted to be supplied with fluid under pressure from said source, a second reservoir, a first valve interconnecting said first reservoir and said second reservoir, means for causing said valve to be normally maintained in the closed position thereof, a second valve connected to said second reservoir and adapted to control a flow of an arc extinguishing blast from said second reservoir adjacent said pair of contacts, and means operative independently of the difference in fluid pressure between said reservoirs for opening said first valve upon separation of said contacts.

2. In a circuit breaker the combination of an arcing chamber, a pair of cooperating contacts arranged in said chamber, contact separating means, a source of fluid under pressure, a first reservoir adapted to be supplied with fluid under pressure from said source, a second reservoir, a first passage means connecting said first reservoir and said second reservoir, a first valve for controlling a flow of fluid through said first passage means, means for causing said valve to be normally maintained in the closed position thereof, a first fluid motor operative independently of the difference in fluid pressure between said reservoirs for opening said first valve, a second passage means connecting said second reservoir and said arcing chamber, a second valve for controlling a flow of fluid through said second passage means, a second fluid motor for operating said second valve, and means for initiating the valve opening stroke of said first fluid motor by the valve opening stroke of said second fluid motor.

3. In a circuit breaker the combination of a pair of cooperating contacts, contact separating means, a source of fluid under pressure, a first reservoir adapted to be supplied with fluid under pressure from said source, a second reservoir, a first valve interconnecting said first reservoir and said second reservoir, means for causing said first valve to be normally maintained in the closed position thereof, a second valve connected to said second reservoir and adapted to control a flow of arc extinguishing blast from said second reservoir adjacent said pair of contacts, means for sequentially opening said pair of contacts and said first valve, said means including a fluid motor for opening said first valve operative independently of the difference of fluid pressure between said reservoirs, and means for supplying said fluid motor with fluid under pressure directly derived from said second reservoir.

4. In a circuit breaker the combination of a pair of cooperating contacts, contact separating means, a source of fluid under pressure, a first reservoir adapted to be supplied with fluid from said source, a second reservoir, a first valve interconnecting said first reservoir and said second reservoir, a blast tube for the passage of a blast of fluid under pressure from said second reservoir adjacent said pair of contacts, a second valve arranged in said blast tube for controlling said blast of fluid under pressure, a fluid motor for operating said first valve, and a passage means for supplying said motor with fluid under pressure, said passage means branching off said blast tube at a point situated downstream with respect to said second valve.

5. In combination, a circuit breaker comprising a pair of cooperating arcing contacts con-

nected in series with a pair of cooperating disconnect contacts, contact separating means for said arcing contacts, a source of fluid under pressure, a first reservoir adapted to be supplied with fluid under pressure from said source, a second reservoir, a first valve interconnecting said first reservoir and said second reservoir, means for causing said valve to be normally maintained in the closed position thereof, a second valve connected to said second reservoir and adapted to control a flow of arc extinguishing blast adjacent said pair of arcing contacts, means for separating said disconnect contacts upon separation of said arcing contacts, and mechanical means actuated by said disconnect contact separating means upon a predetermined movement of said disconnect contacts for opening said first valve.

6. In combination, a circuit breaker comprising a pair of cooperating arcing contacts connected in series with a pair of cooperating disconnect contacts, contact separating means for said arcing contacts, a source of fluid under pressure, a first tank adapted to be supplied with fluid under pressure from said source, a second tank, a first valve interconnecting said first tank and said second tank, a closing biasing means associated with said valve, a second valve connected to said second tank and adapted to control a flow of arc extinguishing blast adjacent said pair of arcing contacts, means for separating said disconnect contacts upon separation of said arcing contacts, a rock shaft for operating said disconnect contact separating means, a fluid motor for operating said rock shaft, and means under the control of said rock shaft for opening said first valve against the action of said closing biasing means.

7. In combination, a circuit breaker comprising cooperating arcing contacts and cooperating disconnect contacts serially connected with said arcing contacts, a source of fluid under pressure, a storage tank adapted to be supplied with fluid under pressure from said source, a breaker tank, a first valve interconnecting said storage tank and said breaker tank, means for normally maintaining said valve in the closed position thereof, a second valve connected to said breaker tank and adapted to control a flow of arc extinguishing blast from said breaker tank adjacent said arcing contacts, and means for sequentially opening said arcing contacts and said disconnect contacts, said means including a common fluid motor for opening said disconnect contacts and said first valve.

8. In combination, a circuit breaker comprising cooperating arcing contacts and cooperating disconnect contacts serially connected with said arcing contacts, a source of fluid under pressure, a storage tank adapted to be supplied with fluid under pressure from said source, a breaker tank, a first valve interconnecting said storage tank and said breaker tank, means for biasing said valve to the closed position thereof, a second valve connected to said breaker tank and adapted to control a flow of arc extinguishing blast from said breaker tank adjacent said arcing contacts, and means for sequentially opening said arcing contacts and said disconnect contacts including a rock shaft adapted to separate said disconnect contacts, and a rocking lever under the control of said rock shaft for actuating said first valve to the open position thereof.

9. In a circuit breaker the combination of a pair of cooperating contacts, contact separating means, a source of fluid under pressure, a storage

tank adapted to be supplied with fluid under pressure from said source, a breaker tank, a first valve interconnecting said storage tank and said breaker tank, a second valve connected to said breaker tank and adapted to control a flow of arc extinguishing blast from said breaker tank adjacent said contacts, means for causing said first valve to be normally maintained in the closed position thereof, a motor operative independently of the difference in fluid pressure between said tanks for operating said first valve, and control means for causing sequential opening of said second valve and said first valve.

10. In combination, a circuit breaker comprising cooperating arcing contacts and cooperating disconnect contacts serially connected with said arcing contacts, means for opening said arcing contacts, a source of fluid under pressure, a storage tank adapted to be supplied with fluid under pressure from said source, a breaker tank, a first valve interconnecting said storage tank and said breaker tank, means for normally maintaining said valve in the closed position thereof, a second valve connected to said breaker tank and adapted to control a flow of arc extinguishing blast from said breaker tank adjacent said arcing contacts, a motor, a common actuating structure operated by said motor for opening said disconnect contacts and said first valve, said structure being also adapted to reclose said disconnect contacts upon separation thereof and to cause closing of said first valve concurrently with any such reclosing.

11. In a circuit breaker the combination of a pair of cooperating contacts, a source of fluid under pressure, a storage tank adapted to be supplied with fluid under pressure from said source, a breaker tank, a first valve interconnecting said storage tank and said breaker tank, means for biasing said valve to the closed position thereof, a second valve connected to said breaker tank and adapted to control a flow of arc extinguishing blast from said breaker tank adjacent said pair of contacts, and common actuating means for opening said contacts and said first valve, said common means being also adapted to reclose said contacts upon separation thereof and to permit said biasing means to close said first valve concurrently with any such reclosing.

12. In a circuit breaker the combination of an arcing chamber, a pair of cooperating contacts arranged in said chamber, a fluid motor for opening said contacts, a source of fluid under pressure, a storage tank adapted to be supplied with fluid under pressure from said source, a breaker tank, a first passage means connecting said storage tank and said breaker tank, a first valve for controlling a flow of fluid through said first passage means, means for causing said valve to be normally maintained in the closed position thereof, a second passage means connecting said breaker tank and said arcing chamber, a second valve for controlling a flow of fluid through said second passage means, and mechanical means for causing said first valve to be opened by said contact opening fluid motor concurrently with any contact opening operation thereof.

13. In a circuit breaker, the combination of a pair of cooperating contacts, contact separating means, a source of fluid under pressure, a first reservoir adapted to be supplied with fluid under pressure from said source, a second reservoir, a first valve interconnecting said first reservoir and said second reservoir, means for causing said valve to be normally maintained in the closed

11

position thereof, a second valve connected to said second reservoir and adapted to control a flow of arc extinguishing blast from said second reservoir adjacent said pair of contacts, a fluid motor for opening said first valve comprising a cylinder and a piston operatively arranged therein, passage means under the control of said second valve for supplying fluid under pressure to said cylinder simultaneously to both ends thereof, and means for causing bleeding of fluid under pressure from said cylinder at a different rate at both ends thereof.

14. In a circuit breaker the combination of a pair of cooperating contacts, contact separating means, a source of fluid under pressure, a first reservoir adapted to be supplied with fluid under pressure from said source, a second reservoir, a first valve interconnecting said first reservoir and said second reservoir, means for causing said valve to be normally maintained in the closed position thereof, a second valve connected to said second reservoir and adapted to admit a flow of arc extinguishing blast from said second reservoir adjacent said pair of contacts, means for reclosing said second valve upon separation of said contacts, and means operative independently of the difference in fluid pressure between said reservoirs for causing opening of said first valve upon reclosing of said second valve.

15. In a circuit breaker, the combination of a pair of cooperating arcing contacts in series with a pair of cooperating disconnect contacts, contact separating means for said arcing contacts, a source of fluid under pressure, a first reservoir, passage means having a relatively small cross-

10
